[57] **CLAIM**

The ornamental design for housing for capsule components
such as thermometers, clocks or compasses, as shown and
described.

DESCRIPTION

FIG. 1 is a first perspective view of a housing for capsule components such as thermometers showing my new design;
FIG. 2 is a second perspective view thereof;
FIG. 3 is a top plan view thereof;
FIG. 4 is a bottom plan view thereof;
FIG. 5 is a left side elevation view thereof;
FIG. 6 is a right side elevation view thereof;
FIG. 7 is a rear elevation view thereof; and,
FIG. 8 is a front elevation view thereof.
